UNITED STATES PATENT OFFICE.

CHARLES O. BLEE, OF FORT WAYNE, INDIANA.

DESIGN FOR A FISHING-REEL.

51,710.

Specification for Design.

Patented Feb. 5, 1918.

Application filed April 12, 1915. Serial No. 20,971. Term of patent 3½ years.

To all whom it may concern:

Be it known that I, CHARLES O. BLEE, a citizen of the United States, residing at Fort Wayne, in the county of Allen and State of Indiana, have invented a new, original, and ornamental Design for Fishing-Reels, of which the following is a specification, reference being had to the accompanying drawing, forming a part thereof.

In the drawing a perspective view of the device is shown.

I claim:—

The ornamental design for a fishing reel, as shown.

In testimony whereof I affix my signature.

CHARLES O. BLEE.
